CLAIM

The ornamental design for a bezel for a system storage controller, as shown and described.

DESCRIPTION

FIG. 1 is a front, right perspective view of the bezel;

FIG. 2 is a front view of the bezel;

FIG. 3 is a left side view of the bezel;

FIG. 4 is a right side view of the bezel;

FIG. 5 is a bottom view of the bezel; and,

FIG. 6 is a top view of the bezel.

The rear view of the bezel is unornamented.

The housing illustrated in broken lines in the drawing figures is considered environmental only and does not form a part of the claimed design.
